MOLDABLE FOOT SUPPORT

Murray D. Cosin, Endicott, N. Y.

Application February 17, 1954, Serial No. 410,756

8 Claims. (Cl. 36—71)

This invention relates to foot supporting devices, and more particularly to devices adapted to be inserted in the toe area of shoes or other footwear for promoting natural action of the foot in walking. The present application is a continuation-in-part of the inventor's pending application, Serial No. 337,035, filed February 16, 1953, now abandoned.

It will be observed that in normal barefoot walking on a soft surface, such as sand, the toes tend to contract and push the surface material into the area immediately behind them, forming a buttress, which the toes may grip. This normal grasping action exercises not only the toe muscles but also the muscles which control the main arch of the foot, and thus serves to keep the entire foot in healthy condition. The buttress thus formed also provides an anchor for the forward part of the foot, limiting the tendency of the foot to pronate and elongate along its longitudinal axis, and increases the area of weight bearing surface, thus providing better weight distribution.

The hard, flat insoles of conventional footwear afford no comparable anchor for the foot in walking, and eliminate much of the natural toe action which would normally maintain the tone of the toe and arch supporting muscles. As a result, constant walking in such footwear, and on the hard surfaces usually encountered, tends to develop strains in the arch supporting muscles and displacement of the bones, particularly in the metatarsal region, as well as loss of tone of the toe muscles. On hard surfaces, furthermore, the concentration of weight on the ball of the foot is likely to produce sore spots and callouses.

Arch supporting devices provide temporary relief for strains and displacements, and improve weight distribution, but such devices discourage, rather than encourage, proper exercise of the foot muscles. For example, metatarsal pads cause extension, rather than contraction of the toes in walking. The corrective exercises ordinarily prescribed to overcome muscular weaknesses of the foot are tedious and time-consuming, and patients rarely practice them with sufficient regularity to achieve satisfactory results.

The object of this invention is to provide a moldable insert adapted to be installed in the forward part of a shoe or other footwear, which simulates the buttress naturally formed by the grasping action of the toes in walking on soft sand, or a similar surface.

In one form, the device here described consists in general of a pad of resilient, somewhat plastic material, extending over the entire inner surface of the shoe or sole, having an insert of more flowable material in the general region of the area between the heads of the metatarsal bones of the foot and the proximal phalangeal shafts of the toes. The pad is formed of two layers, or is split through the forepart, and the flowable insert material trapped between the less plastic layers so as to limit its flow. The pad may be placed in the shoe as a separate inner sole or permanently built into the shoe. The pad is preferably made of a material which will take a perma-

2

nent imprint while retaining a considerable amount of resilience. The insert is made of a slow flowing, pressure moldable material which retains its plasticity indefinitely, but is sufficiently cohesive to retain its molded shape when pressure is removed. After a short period of wear, the pad adapts itself to the contour of the under surface of the wearer's foot, and the more flowable insert becomes molded to fill the space under the toes created by their grasping action during walking and thus provide a buttress similar to that formed by the toes in walking barefoot on a soft surface. This buttress promotes constant and active use of the toes in the normal manner during walking so as to restore and maintain their muscle tone, and also helps to eliminate arch strains by providing an anchor for the forepart of the foot. An inner sole thus constructed also affords better weight distribution over the under surfaces of the foot than a flat surface, thus reducing concentration of pressure on the heel and ball. As well as providing an excellent corrective for foot ailments developed in walking on hard surfaces, the inner sole is of great benefit in maintaining the health and comfort of normal feet.

In another form, the pad may consist of an impervious envelope enclosing a moldable material which remains permanently plastic. The envelope may be attached in various ways to the sock lining of a shoe or slipper, or may be built into the inner sole of the shoe.

In the drawings illustrating the invention;

Fig. 1 is a longitudinal cross-section of a shoe in which a separate inner sole, constructed according to the invention has been installed;

Fig. 2 is a top view of an inner sole, constructed according to the invention, which has been worn sufficiently to mold the insert to the desired contour;

Fig. 3 is a transverse cross-section of the inner sole taken along the line 3—3 of Fig. 2;

Fig. 4 is a detail view of the separate parts used to make up the inner sole;

Fig. 5 illustrates a modified construction of the inner sole;

Fig. 6 illustrates the inner sole as adapted to be built into a shoe;

Fig. 7 illustrates a moldable toe insert, constructed according to the invention, installed in a conventional shoe insole;

Fig. 8 is a cross-section of a strip of material from which a modification of the insert may be formed;

Fig. 9 illustrates one step in forming a toe insert from the strip of Fig. 8;

Fig. 10 is a plan view of a completed insert formed from the strip of Fig. 8;

Fig. 11 is a cross-section taken along line 11—11 of Fig. 10;

Fig. 12 is a cross-section of a modification of the insert of Fig. 10;

Fig. 13 is a bottom view of a sole pad or sock lining, with a modification of the insert installed;

Fig. 14 is a plan view of a toe sling pad incorporating the insert;

Fig. 15 is a side view of the sling of Fig. 15.

In Fig. 1 the inner sole is shown installed in a conventional shoe having a sole 10 and insole 11 between which is interposed a layer of filler material 12. The inner sole itself as illustrated in Figs. 1, 3 and 4, consists of a resilient bottom layer 13, a resilient upper layer 14, each about $\frac{1}{16}$ in. thick or thicker, a plastic insert 15, and sock lining 16 of material ordinarily used for the purpose such as thin natural or artificial leather, or cloth.

The resilient layers 13 and 14 are made of a material which will take a permanent imprint of the foot after a short period of wear while retaining a certain amount of resiliency. A composition of uncured sponge rubber and

cork, such as that disclosed in Patent Number 2,288,686, to Daniels, has been found especially suitable for the purpose, but other types of materials, such as vulcanized or foam rubber or plastic materials, or moldable leather may be used.

The insert is made of a flowable material which will not take a permanent set and has a low rate of flow at body temperature. A certain amount of tackiness at this temperature is also desirable, as it aids in preventing too rapid spread of the insert material between the resilient layers. A compound of cork, petroleum asphalt, and plasticizer, used for pipe insulation and sold under the trademark "No-Drip" by the G. W. Mortell Co., has been found suitable. Other similar materials may be used however, the chief requirements being that the insert material be sufficiently flowable under pressure to form the relatively high ridge required to fill in the space behind the toes, and at the same time sufficiently stiff and cohesive so as to retain its molded shape and not to spread beyond the desired area.

In the inner sole as manufactured, the insert is about $\frac{1}{32}$ in. to $\frac{1}{16}$ in. thick throughout the roughly triangular in outline as shown in Fig. 4, and has a somewhat concave edge 30. It is placed on the lower pad layer 13 with the front corner tilted somewhat toward the large toe area, in the position indicated by the dotted outline 17. The upper pad layer 14 is then placed on top and cemented to the lower layer up to the edge of the insert, thus trapping the insert material and restricting its flow. The sock lining 16 is cemented to the upper pad layer. Any suitable adhesive such as rubber cement may be used. For better seating in the shoe, the under edge of the assembled inner sole may be tapered all around, as indicated at the heel edge 18, in Fig. 1 and the side edges 19 and 20 in Fig. 3.

After a short period of wear the insert becomes molded by the wearer's foot to the general shape shown in Figs. 1, 2 and 3. The major bulk of the insert material is pushed up into an arcuate ridge 22 which conforms to the hollow between the toes and the ball of the foot. This ridge is high in the middle and tapers downward toward the outer edges. Depressions 23, 24, 25, 26 and 27 are formed around the forward edge of the insert to conform to the balls of the toes, and the rear part 28 is flattened out to fit the ball of the foot. The upper pad 14 also shapes itself to the overall contour of the under surface of the foot.

In the modification of Fig. 5, the separate resilient layers 13 and 14 are replaced by a single layer 29, approximately $\frac{1}{8}$ in. thick which is split through the forepart to receive the insert 15. After the insert is in place, the split portion is cemented together around the edges.

Fig. 6 illustrates a composite insole incorporating the moldable inner sole and adapted to be built into a shoe in place of the conventional flat insole. The insert 15 and upper and lower pads 13 and 14 are assembled as in the separate inner sole and cemented to the conventional insole 11; the edges of the pads extending to the edges of the insole. The assembly is then attached to the upper in the usual manner. In certain types of footwear, particularly in women's shoes, it may be preferable to have the moldable inner sole cover only the forepart of the shoe. In this case the inner sole terminates at the arch of the shoe, the rear edge being suitably tapered.

Fig. 7 illustrates another type of permanent installation of the toe insert in a shoe. Here the conventional leather insole 11 is split in the forepart, in much the same manner as pad 29 in Fig. 5. The insert 15 is put in place between the split portions of the insole forepart, and the portions cemented together all around the insert. The insole is then assembled in a shoe in the conventional manner.

Figs. 10, 11 and 12, illustrate an insert in which the moldable plastic material 31 is a silicone fluid or gum. As the first step in the preferred method for making such an insert, a layer of silicone compound 32 is spread be-

tween two strips 33 and 34, of a rubber hydrochloride film such as that sold under the trademark "Pliofilm" by the Goodyear Tire & Rubber Co., or other flexible material. A silicone layer about $\frac{1}{32}$ in. to $\frac{1}{16}$ in. thick placed between two Pliofilm has been found generally satisfactory. Insert blanks 35 having the general shape of a right triangle with a slightly curved hypotenuse are then die cut from the strip of Fig. 8, as shown in Fig. 9. A blank 35 is then placed between two layers 37 and 38 of polyethylene film cut to the same general shape but of slightly larger size than the blank, and the margins of the polyethylene film layers heat sealed along the line 39 all around the blank. The heat sealing is preferably performed by means of a die which fits closely enough around the blank to prevent trapping of any substantial amount of air, the die must yet have enough clearance to avoid putting pressure on the blank and squeezing the silicone compound out from between the Pliofilm layers, as silicone compound in the margin would prevent the polyethylene film layers from sealing properly. The silicone is thus trapped in a leak-proof, flexible envelope.

Another method of confining a silicone compound to form a moldable toe insert is to dip one of the blanks 35 in latex and allow the latex to dry, for forming a unitary envelope 40 as shown in Fig. 12.

The polyethylene film or latex covered silicone inserts may be installed in a pad of either of the types described in Figs. 1-5, or may be installed in a conventional insole, as shown in Fig. 7. The insert is placed in a right shoe for example, with the apex 42 about on the center line of the shoe, $\frac{1}{2}$ inch to 2 inches back from the toe of the sole, the curved edge 43 about parallel to the right outer edge of the sole, and the rear edge slanting slightly forward from right to left. The trapped silicone is molded by wear to form the desired ridge behind the toes. The size of the insert may be varied for use in men's, women's and children's shoes. For an average man's shoe, however, the size of the blank 35 may be about $1\frac{1}{8}$ inches from the rear edge 41 to the apex 42, and about 2 inches wide at the rear.

In Fig. 13, the insert blank is shown attached to the bottom of a thin sole pad or sock lining 45. This view represents the under side of a pad or lining for the right foot. The insert blank is laid in place against the under side of the pad, and covered by a patch 46. The patch is secured by a row of close stitching 47 around the edge of the insert blank. Preferably a layer of latex cement, or similar adhesive is applied around the margin 48 of the patch before stitching so as to ensure a complete seal around the insert. Alternatively, the stitching may be omitted and the patch attached by cement alone. The assembled sock lining and insert may be installed permanently in a shoe, or may be glued to a resilient layer such as pad 13, to form a removable inner sole.

Fig. 14 shows a pad for the forward part of the foot only, held in place by a toe sling. An insert of the type shown in Fig. 11 or 12 is placed in the split forepart of a sponge rubber pad 48 to which are attached an instep strap 49 and a toe strap 50. This pad is held on the straps and is convenient for wear in bedroom slippers or other footwear. The moldable insert becomes molded to the desired ridge form and has the same effect as when installed in a shoe.

The type of materials which are suitable for making the sealed type of insert are permanently plastic, slow-flowing, non-resilient substances such as silicone fluids, oils, or gums. For example difunctional polysiloxane, disubstituted polysiloxane, and dialkyl-aryl-alkenyl polysiloxane, or combinations of these substances or other substances with similar properties may be used. Inert fillers such as calcium carbonate, ground cork or similar materials may be added to provide greater bulk and thus decrease the cost. The essential characteristics of a material used for this purpose are plasticity, fluidity, softness and non-resiliency. The material must be one which re-

tains these characteristics indefinitely and is not substantially affected by temperature changes. The material should flow readily under light pressure but should be non-resilient and sufficiently cohesive to retain an imprint when the pressure is removed.

The separate self contained type of moldable insert gives the wearer all the benefits resulting from the natural toe action, and has the advantage of taking only a negligible amount of space in the shoe. In fact, the insert, when molded occupies only the space behind the toes which would otherwise be empty, so that the fit of the shoe is not altered. The insert may thus be used in a shoe of the wearer's normal size.

What is claimed is:

1. A toe grip for footgear, comprising an insert of plastic material which is sufficiently slow flowing to remain substantially static when unstressed and to resist displacement by light external pressure, but is sufficiently flowable at body temperature to be molded by action of the human foot in walking and which is adapted to retain the aforesaid characteristics substantially permanently, and means for confining said material in a piece of footgear to the sole region disposed, when the footgear is worn, to underlie the toe cavity of the foot between the heads of the metatarsal bones and the balls of the toes.

2. A toe grip for footgear, comprising an insert of plastic material which is sufficiently slow flowing to remain substantially static when unstressed and to resist displacement by light external pressure, but is sufficiently flowable at body temperature to be molded by action of the human foot in walking and which is adapted to retain the aforesaid characteristics substantially permanently, and means for confining said material in a piece of footgear to a sole region adapted, when the footgear is worn, to underlie the toe cavity of the foot, said region being bounded by a first transverse line disposed to lie ahead of the heads of the metatarsal bones of the foot, by a second line extending forward from the first in the vicinity of the large toe of the foot, and by a third line extending rearward from the second to the first along the vicinity of the balls of the other toes of the foot.

3. A toe grip as described in claim 2, said first and second lines being substantially straight and at right angles to one another, and the third line being somewhat bowed outward.

4. A toe grip for footgear, comprising a sealed impervious envelope, and an insert of plastic material which is sufficiently slow flowing to remain substantially static when unstressed and to resist displacement by light external pressure, but is sufficiently flowable at body temperature to be molded by action of the human foot in walking and which is adapted to retain the aforesaid characteristics substantially permanently, said insert being confined in said envelope.

5. A toe grip device for footgear, comprising a pair of layers of flexible material adapted to be disposed, one above the other, in a piece of footgear and to extend over the sole part thereof, and an insert of plastic material which is sufficiently slow flowing to remain substantially static when unstressed and to resist displacement by light external pressure, but is sufficiently flowable at body temperature to be molded by action of the human foot in walking and which is adapted to retain the aforesaid characteristics substantially permanently, said insert

being disposed between said layers in the region disposed, when the footgear is worn, to underlie the toe cavity of the foot between the heads of the metatarsal bones and the balls of the toes, said layers being secured together around said insert so as to confine the insert to said region.

6. A toe grip device for footgear, comprising a piece of flexible material adapted to be disposed in a piece of footgear and to extend over the sole part thereof, said piece having a forepart comprising upper and lower laminations, and an insert of plastic material which is sufficiently slow flowing to remain substantially static when unstressed and to resist displacement by light external pressure, but is sufficiently flowable at body temperature to be molded by action of the human foot in walking and which is adapted to retain the aforesaid characteristics substantially permanently, said insert being disposed between said laminations in the region disposed, when the footgear is worn, to underlie the toe cavity of the foot between the heads of the metatarsal bones and the balls of the toes, said laminations being secured together around said insert so as to confine the insert to said region.

7. A toe grip device for footgear, comprising a piece of flexible material adapted to be disposed in a piece of footgear and to extend over the sole part thereof, an insert of plastic material which is sufficiently slow flowing to remain substantially static when unstressed and to resist displacement by light external pressure, but is sufficiently flowable at body temperature to be molded by action of the human foot in walking and which is adapted to retain the aforesaid characteristics substantially permanently, said insert being disposed on the under side of said piece in the region disposed, when the footgear is worn, to underlie the toe cavity of the foot between the heads of the metatarsal bones and the balls of the toes, and a patch of flexible material disposed under said insert and secured to said piece all around the insert so as to confine the insert to said region.

8. A toe grip for a piece of footgear, comprising a pad of permanently deformable material adapted to be disposed over the sole of a piece of footgear, said pad having a forepart comprising upper and lower layers, and an insert of plastic material which is sufficiently slow flowing to remain substantially static when unstressed and to resist displacement by light external pressure, but is sufficiently flowable at body temperature to be molded by action of the human foot in walking and which is adapted to retain the aforesaid characteristics substantially permanently, said insert being disposed between said layers in the region disposed, when the footgear is worn, to underlie the toe cavity of the foot between the heads of the metatarsal bones and the balls of the toes, said layers being secured together around said insert so as to confine the insert to said region.
